(57) **CLAIM**

The ornamental design for a screen protector installation device, as shown and described.

DESCRIPTION

FIG. 1 is a top front perspective view of a screen protector installation device, showing my new design;

FIG. 2 is a bottom front perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines throughout the drawing figures depict portions of the screen protector installation device that form no part of the claimed design. The broken lines and regions bounded by broken lines form no part of the claimed design.

1 Claim, 8 Drawing Sheets
